[57] CLAIM

The ornamental design for a dashboard panel with a display, as shown and described.

DESCRIPTION

FIG. 1 is an oblique view of a dashboard panel with a display showing my new design;

FIG. 2 is a top plan view thereof;

FIG. 3 is a front elevational view thereof;

FIG. 4 is a left side elevational view thereof;

FIG. 5 is a bottom plan view thereof;

FIG. 6 is a right side elevational view thereof; and,

FIG. 7 is a rear elevational view thereof.

The broken line showing the display is for illustrative purposes only.
